[57] **CLAIM**

The ornamental design for a micrometer organizing and protecting device, as shown and described.

DESCRIPTION

FIG. 1 is a perspective view of the micrometer organizing and protecting device of my new design;

FIG. 2 is an end view of the device, the opposite end being a mirror image of the end shown;

FIG. 3 is a sectional view taken on the line 3—3 of FIG. 1;

FIG. 4 is a side elevational view taken from the left side of FIG. 1;

FIG. 5 is a top plan view of the device;

FIG. 6 is a side elevational view taken from the right side of FIG. 1; and,

FIG. 7 is a bottom plan view.

The broken line showing of micrometers is for illustrative purposes only and forms no part of the claimed design.

FIG. 4

FIG. 5

FIG. 6

FIG. 7
